DEVICE FOR SECURING A HEAD TO A
BARRELHarry C. Wilcox, Milwaukee, Wis., assignor to
Pressed Steel Tank Company, Milwaukee, Wis.,
a corporation of Wisconsin

Application October 3, 1931, Serial No. 566,624

4 Claims. (Cl. 220—61)

This invention relates in general to metal containers or receptacles such as barrels and more particularly to improved means for releasably securing a head or closure in fluid tight engagement with the barrel.

One of the principal objects of the present invention is to provide a device of this character which is readily and easily operable without the use of any special tools for the purpose of securing the head in fluid tight engagement with the barrel or for the purpose of releasing the head for removal.

Another important advantage resides in the feature of having the device self-locking when it is moved to the position in which it secures the head in fluid tight engagement with the barrel.

Other objects and advantages reside in certain novel features of the construction, arrangement and combination of parts which will be herein-after more fully described, and particularly pointed out in the appended claims, reference being had to the accompanying drawing forming a part of this specification, and in which:

Figure 1 is a view in side elevation showing a barrel having a removable head equipped with a releasable securing means embodying the present invention;

Figure 2 is a fragmentary view in side elevation on an enlarged scale more clearly illustrating the details of construction of the releasable securing means;

Figure 3 is a view in horizontal section taken in the plane of line 3—3 in Figure 2 and looking in the direction of the arrows; and

Figures 4 and 5 are fragmentary views in vertical section taken on lines 4—4 and 5—5, respectively, of Figure 2.

Referring to the drawing, the numeral 1 designates a metal receptacle or container shown for the sake of illustration in the form of a barrel. The upper end of the barrel is open and may be provided with a head or rim 2. A head 3 may be applied to the upper open end of the barrel to close the same and has its peripheral portion in the form of a curved flange-like structure 4 adapted to be seated on the bead 2 or on a gasket (not shown) which may be provided on the bead.

The head is fastened in position to close the open end of the barrel and to have its flange 4 in fluid tight contact with the bead 2 by means of a contractible metal clamping ring 5. As shown, the metal ring 5 is made of channel form or concave on its inner side to fit over and engage with the outer side of the flange 4 of the head 3 and the underside of the bead 2 to draw and hold

these parts tightly together when the ring is contracted thereon. This action of the ring is enhanced by constructing the channel in the clamping ring so that it has outwardly converging opposing walls to engage with the bead or rim 2 of the barrel and the flange 4 of the head. The ring is made contractible by splitting or severing it transversely and is sufficiently resilient to adapt it to be contracted for securing the head in position and to be expanded for removal.

The ring is expanded and contracted by means of a specially constructed manually operable toggle organized with the ring in a novel manner. As illustrated, one end of the ring 5 has a lug 6 welded or otherwise suitably secured thereto and projecting downwardly therefrom on the outside of the barrel. A second lug 7 is secured to the ring 5 adjacent its opposite end and projects downwardly from the ring on the outside of the barrel. The lug 6 is provided with an opening through which the shank of a stud or screw 8 is adjustably fitted. A nut 9 is threadedly engaged with an end of the shank of the screw which projects beyond the lug and abuts one side of the lug. By turning the nut the stud or screw 8 may be adjusted. The head of the stud or screw is pivotally connected as at 10 to link members 11. Two link members 11 are provided but they function as a single link. The opposite ends of the link members from those connected to the stud or screw 8 are pivotally connected as at 12 to an intermediate portion of a handle 13. The inner end of the handle 13 is fulcrumed or pivotally connected to the lug 7 as indicated at 14. The free end of the handle 13 is offset as at 15 to facilitate grasping thereof in the closed or locked position of the parts.

It will be noted from Figure 3 that the manually operable toggle mechanism is so designed that in the position thereof where the toggle contracts the ring to secure the head to the barrel, the toggle is self-locking, that is to say, the line between the pivotal connections or centers 10 and 12, lies inwardly of the fulcrum or center 14 or between this fulcrum or center 14 and the barrel.

The handle 13 and link members 11 are of arcuate form and concentric with the barrel and clamping ring in the closed or locked position of the device. In this way, a compact and practical structure is had and the parts are located substantially within the lateral or peripheral confines of the ring 5 and hence effecting protection thereby. The lugs 6 and 7 have their portion which connects with the link member 11 and

handle 13 offset inwardly under the clamping ring 5 for these purposes.

With the head applied to the barrel it may be secured in position by positioning the ring in operative relation to flange 4 and bead 2 when the ring is expanded and the toggle open. The handle 13 is then pushed inwardly toward the barrel. This causes the pivotal connection 12 to swing in such manner that it exerts a pull to the right, as viewed in Figure 3, on the link members 11, stud 8 and lug 6 and a thrust to the left (Figure 3) on the lug 7 thereby contracting the ring 5 into secure engagement with the flange 4 and bead 2. As the lever 13 reaches the point where the line between the centers 10 and 12 passes the center 14, the strain exerted on the parts causes the handle and link 11 to snap into the locked position shown in Figure 3. The ring 5 may be released and the head removed by grasping the offset portion 15 of the handle and pulling the handle away from the barrel which results, after the initial movement of the handle, in the handle exerting a pull to the right on the lug 7 (see Figure 3), and a thrust to the left of lug 6, as viewed in Figure 3, thereby expanding the ring 5. The degree and effectiveness of the locking action may be regulated by adjusting the nut 9. By having the toggle arrangement organized with lugs which are disposed on the outside of the barrel, the toggle is easily accessible and readily and easily manipulated. And further, it is self-locking in the secured position of the ring 5. The structure is rugged and durable and while easily manipulated is positive and secure in its locking action and safe against accidental disengagement or release. Although disposed on the outside of the barrel, the device is effectively protected by the overhanging structure of the barrel, bead and clamping ring (see Figures 4 and 5) and is arranged so that any impacts or the like tend to increase the locking effect rather than to release the device.

In some instances it may be desirable to enhance the character of the fluid tight seal between the head and the barrel. This may be accomplished by applying the clamping ring and bringing it into clamping engagement with the head and barrel in the manner above described. After the toggle has assumed a locked position the nut 9 may be tightened up, that is to say, turned to pull the stud 8 to the left as viewed in Figure 3, with the result that the toggle is more positively urged to its locked position and the clamping action of the ring 5 increased.

55. The invention claimed is:

1. A device for securing a removable head to a barrel comprising a split clamping ring, lugs secured to the ring at or adjacent the ends thereof and projecting downwardly on the outside of the barrel, said lugs having portions offset inwardly beneath the ring, and a toggle including a link pivotally connected to the offset portion of one of said lugs, a handle pivotally connected intermediate its ends to the link and permanently fulcrumed at one end to the offset portion of the other of said lugs, said handle swinging inwardly toward the barrel to close the toggle and contract the ring whereby to secure the head to the

barrel, said toggle being self-locking in a position in which the ring is contracted and lying beneath the ring and substantially within the lateral confines thereof when in the locked position.

2. A device for securing a removable head to a barrel comprising a split clamping ring, engageable with the head and with the barrel, lugs secured to the ring at or adjacent its ends and projecting downwardly on the outside of the barrel and having inwardly offset portions, a toggle including an arcuate link pivotally connected to the offset portion of one of said lugs, and an arcuate handle permanently fulcrumed at one end to the offset portion of the other of said lugs and pivotally connected intermediate its ends to said link, said handle swinging inwardly toward the barrel to close the toggle and contract the ring, said handle and said links lying within the lateral confines of the ring on the outside of the barrel and in concentric relation thereto in the closed position of the toggle.

3. A device for securing a removable head to a barrel comprising a split clamping ring, engageable with the head and with the barrel, lugs secured to the ring at or adjacent its ends and projecting downwardly on the outside of the barrel and having inwardly offset portions, a toggle including an arcuate link pivotally connected to the offset portion of one of said lugs, and an arcuate handle permanently fulcrumed at one end to the offset portion of the other of said lugs and pivotally connected intermediate its ends to said link, said handle swinging inwardly toward the barrel to close the toggle and contract the ring, said handle and said links lying within the lateral confines of the ring on the outside of the barrel and in concentric relation thereto in the closed position of the toggle, said parts being so designed that a line between the centers of the pivotal connections between the link and lug and the link and handle lies inwardly of the pivotal connection between the handle and the lug in the closed position of the toggle whereby said toggle is self-locking.

4. A device for securing a closure to a barrel comprising a split clamping ring engageable with the closure and with the barrel and a manually operable self-locking toggle mechanism for securing and releasing said clamping ring, said toggle mechanism having as its parts a link pivoted to a portion of the ring on one side of the split thereof and a handle pivoted to a portion of the ring on the other side of the split and also pivoted to the link, the parts of said toggle mechanism being disposed on the outer side of the barrel and beneath the ring, the connections between the parts of the toggle mechanism and the ring permanently and operatively uniting the same into a unitary assembly in all positions and adjustments, said handle and said link swinging inwardly toward the barrel to close the toggle and contract the ring whereby to secure the closure to the barrel, the parts of said toggle being self-locking in a position in which the ring is contracted and lying substantially within the lateral confines of the ring so as to be protected thereby in the locking position of the mechanism.

HARRY C. WILCOX.
